UNITED STATES PATENT OFFICE.

DANIEL B. LUTEN, OF INDIANAPOLIS, INDIANA.

MASONRY AND CONCRETE STRUCTURE.

No. 852,971.

Specification of Letters Patent.

Patented May 7, 1907.

Application filed June 30, 1906. Serial No. 324,233.

To all whom it may concern:

Be it known that I, DANIEL B. LUTEN, a citizen of the United States, residing at Indianapolis, in the county of Marion and State of Indiana, have invented new and useful Improvements in Masonry and Concrete Structures, of which the following is a full, clear, concise, and exact description, reference being had to the accompanying drawing, forming a part of this specification.

My invention relates to improvements in masonry or concrete structures, and applies more particularly to the construction of bridges, viaducts and the like built of masonry reinforced by embedded tension members.

One object of the invention is to provide a bridge, etc., structure that shall be durable and highly efficient in character, of simple and inexpensive construction and attractive in appearance.

Another object of my invention is to gain increased strength in such structures and also to diminish the amount of material used and thus secure reduced cost of construction combined with increased strength.

These objects I accomplish by the method of construction and arrangement and combination of material hereinafter described.

There are various other objects which will be readily understood upon reference to the accompanying drawings illustrating my invention in the preferred forms and the construction of its several features, wherein:

Figure 1 is a longitudinal sectional view through the middle rib of Fig. 3; Fig. 2 is an elevation showing a pointed or Gothic arch under the railings, changing to oval under the roadway; Fig. 3 is a transverse section taken on the dotted line 3—3 of Fig. 2; the left half looking toward the abutment, and the right half looking toward the pier; Figs. 4 and 5 show reinforcements of double and single bar type respectively; with laps, welds or joints at points of zero bending moment.

Fig. 1 of the drawings shows in section part of an arch extending from the bank 1 to the pier, and provided with an abutment consisting of ribs 4 and 5 which converge toward the springing line and which terminate in a transverse footing 3. This abutment is built by laying the upper rib 5 on earthfilling 6. In

order to secure a high springing suitable for street crossings, a false bench wall 7 is extended from the springing downward. It may be attached to and carried by the arch (Fig. 4) or may be built on a separate footing (Fig. 1), and is adapted to give the intrados of the arch a high springing point without the use of the mass of masonry in the abutment that would be required if the abutment and bench wall were cast in one solid piece. The bench wall may be extended beyond the faces of the arch in wings such as 7^a, to hold the toe of the slope, and earth filling allowed to fill in behind the wings and bench wall to partly fill the opening behind the wall. The arch will then appear to have a solid abutment except for the slight line of junction along the springing. The reinforcement rib shown in Fig. 1 and in the left half of Fig. 3, consists of pairs of angles 8 and 9, following the intrados and extrados respectively. The pairs of angles are joined by a web lacing bars 10 in the region of the moments only. At the left of Fig. 1 the rib is shown extended into the abutment to secure anchorage. At the right by making the curve of the arch elliptical for intrados it becomes impossible for it to fail by rupture in that region of intrados, hence the intrados member of the rib is omitted and the extrados member is continued over the haunches to the pier 2 where it overlaps a similar member of the adjacent arch and is thus securely anchored. By this means the ribs may be placed without any accurate fitting and yet bond the two arches together effectually.

Hinges have long been used in arches to determine the position of the equilibrium curve or to allow settlement. Arches have usually been designed with one hinge at the crown or with one hinge at each abutment, or with all three hinges. The introduction of a hinge absolutely prevents the arch from resisting a bending moment at that point. In a continuous arch having no hinges, the moments are a maximum at the crown and springings, and pass through zero at an intermediate point where the shear is a maximum. By introducing hinges at the crown or springing, these conditions will be upset and the arch very much weakened unless strengthened by heavier abutments and heavier ribs at the haunches. The same re-

sults as to determining the curve of equilibrium and allowing for settlement may be achieved by introducing two hinges at the two points of minimum moment (Figs. 1 and 5). At the right of Fig. 1 at 12 a lead plate hinge of ordinary or desired construction is suggested, and at the left at 13, a connecting or splicing plate is shown riveted to both members at the point of zero moment. My invention is not only the placing of hinges at the points specified but also the concentration of weak spots which result from hinging, welding, splicing, etc., at these points where they will not weaken the structure. As an improvement I contemplate the use of a heavy lower member for that portion of the rib near the intrados at the crown and a light upper member together with a light member connected to the hinge 12 and extending over the haunches and anchored in the pier. A further improvement would be the omission of the web lacing member except at the regions of shear, and the improvement might be carried to the point where the upper member of the rib would be omitted over the crown and the lower member at the haunches; the reinforcement then consists of an intradosal angle over the crown and an extradosal angle over the haunches joined to the intradosal angle by a shearing plate where they overlap. But it is to be noted that in arches of more than one span a load on one span may tend to cause the adjacent span to rise at the crown and thus fail, but which may be resisted by a light reinforcement at the extrados above the crown.

Fig. 2 is an elevation showing an arch pointed or Gothic at the spandrel faces 14, changing to oval under the roadway 15. (See also Fig. 3). The arch is constructed with Gothic ends because the spandrel loading is vertical, which calls for a curve different from that of the earth-filled loading which is nearly normal. A stone spandrel or railing is even more certain than a concrete spandrel to produce vertical loading, hence the advantage of Gothic end construction in such cases. An ice breaker 16 extends vertically upward from the conical cap 17 of the rounded end of the pier 2, and is made up of two surfaces formed to constitute a wedge that slopes back toward the arch and flattens into the spandrel face at the coping 18. An extension 19 of the spandrel wall rests in the embankment and aids the abutment and bench wall in supporting the load.

Fig. 3 shows in cross section an arch construction which is economical of masonry material. On the left side reinforcing ribs and on the right side double bars are shown embedded in ribs 21 of masonry. An arch drum 22 connects the ribs and is reinforced by rods 23 passing through the ribs and sagging near the intrados of the drum between

the ribs. The outside ribs 24 are built up to 65 extend above the level of the roadway and constitute railings for the bridge or viaduct; the space between the rails up to a suitable height is filled in to form the roadway. The dotted line near the springing of Fig. 3 is to show the possible line of division in case the wing and false wall are built on footings. If the false wall is suspended, this line will not appear, and the spandrel wall might be carried across the opening between the parts of the abutment and no wings be used. If the wings are used, the openings need not be closed, but the earth filling will fall back into the opening and close it.

Fig. 4 shows an arch structure having reinforcements of the double bar type; the heavier sections passing through the tension regions and the lighter through the compression regions; the laps, welds or joints of the sections being made at the point of zero moment; that is, at the point 25, substantially midway between the center of the crown and the springing. It will be understood that increase of metal may be secured by adding sections at the crown and at the haunches, or by increasing the cross section of the sections of metal. In this form of structure, the abutment consists of a horizontal member and a vertical member, the vertical member 7 having its back face inclined upward away from the stream and having vertical reinforcing members 26 embedded, which are joined to the horizontal members in the body of the structure. Occasional vertical masonry ribs join the ends of the two members of the abutment, and have embedded tension members 27 connecting the vertical tension members 26 with the horizontal tension members 28. In the above structure the vertical pressure is not transmitted to the base of the vertical member, but is carried by the horizontal member, and the horizontal thrust is carried by the vertical member at its back face. An advantage of this abutment is that it may be built without destroying the bearing surfaces of the embankment, since earth material excavated is not filled back.

Fig. 5 shows an arch in which the reinforcement members 31 are of the single bar type, and welded, spliced or lapped at the point 32 of zero moment. Vertical reinforcing members 33 in the abutment 30 are joined to the members 31. Arches are ordinarily designed to fit the loading so far as possible, that is, so that the arch rib will follow the curve of equilibrium for the loading. If an excessive load be concentrated at any point, the curvature should be increased at that point to resist it. Where the arch rib joins the abutment, it has been customary to apply a considerable amount of backing as shown by the dotted line 29, to increase the weight of the abutment. The mass of ma-

sasonry in the lower inner corner of the abutment, however, plays no part, except to provide a springing face for the arch. If this latter mass of masonry be suspended from the arch rib as is possible in reinforced concrete construction, a concentrated load is thus added to the arch rib at the very point where it is desirable to increase its curvature to avoid the waste of material due to backing. It is only necessary that the arch rib be bonded to this mass of masonry by tension members as any tendency of the rib to buckle will at once compel it to assume this additional loading.

15 Other modifications will suggest themselves to those skilled in the art, but the divers forms shown sufficiently illustrate the general nature of my invention.

In the claims I use the word "bar" as a generic term intending thereby to include rods, plates, cabled or built-up bars or metal shapes, of any kind analogous to bars, strips or rods.

Having thus described my invention what 25 I claim and desire to secure by Letters Patent is:

1. A concrete arch having embedded steel angles in pairs following intrados and extrados closely, with web lacing riveted between, and spliced at points of calculated change of moment.

2. A concrete arch reinforced with a curved beam made up of angle bars in pairs near intrados and near extrados and web lacing between, embedded in a rib of concrete surrounded by earth filling.

3. A concrete arch reinforced with curved beams spliced near points of minimum bending moment.

4. A concrete arch having heavy angle bars embedded near interior crown and exterior haunch and lighter angle bars near exterior crown and interior haunch, and web lacing between.

45 5. A concrete arch having metal reinforcement near exterior crown and interior haunch and heavier metal reinforcement near interior crown and exterior haunch.

6. A reinforced concrete arch with splices or welds in the reinforcement at points of minimum moment.

7. A concrete arch with hinges near points of calculated change of moment.

8. A concrete arch with a hinge approximately midway between crown and springing.

9. A concrete arch having reinforcement near both surfaces alternately heavy and light on opposite sides of points of calculated 60 change of moment.

10. An arch reinforced near extrados and intrados, junctions in the reinforcement near the points of change of moment, and after-

nately lighter and heavier reinforcement on opposite sides of the junctions.

11. A concrete arch reinforced with embedded tension members near each surface in alternately heavy and light sections.

12. A concrete arch with external projecting ribs reinforced near intrados and extrados 70 continuously.

13. An arch consisting of vertical curved ribs of concrete joined by a transverse inner ring of concrete.

14. A ribbed concrete arch with longitudinal reinforcement near intrados and extrados, and transverse reinforcement near intrados only.

15. The combination of curved angle bars in pairs with web lacing between, embedded 80 in ribs of concrete joined near the intrados by a thinner transverse concrete member.

16. A concrete arch reinforced with ribs consisting of a pair of angle bars following closely the intrados and another pair following closely the extrados, diagonals joining the pairs of angles and a thin ring of concrete joining the ribs at intrados.

17. A concrete arch with oval intrados and reinforced near intrados and extrados at 90 crown and near extrados alone at haunches.

18. A concrete arch with oval intrados and light reinforcement near extrados at crown, and heavier reinforcement near intrados at crown and near extrados at haunches.

19. In a series of concrete arches, embedded reinforcement overlapping and embedded in concrete piers.

20. A pier support for two abutting arches with embedded reinforcement passing from the extrados of one arch into the other to secure anchorage.

21. A concrete abutment consisting of three or more members substantially parallel to its axis.

22. A concrete abutment inclosing on all sides longitudinally a mass of earth filling.

23. A concrete abutment with a downwardly tapering projection at end of span.

24. An abutment having a continuous longitudinal vertical member tapering downward.

25. A concrete arch with a transverse wall suspended from the rib.

26. A concrete arch with a curtain wall at 115 end of span suspended from the arch.

27. A concrete arch with suspended integral loading.

28. A concrete arch with load suspended from intrados and a corresponding change 120 of curvature in arch rib.

29. A concrete arch having a pointed Gothic form combined with an oval form.

30. A concrete arch with pointed crown at spandrel and oval crown under roadway.

31. An oval concrete arch having stone

faced spandrel supported on pointed Gothic arch.

32. An ice breaker for a pier, consisting of a double helicoidal surface of upwardly decreasing wedge shaped section.

33. A pier with cylindrical end and conical cap with an inclined curved surface joining cap of pier to coping of spandrel.

In witness whereof I have hereunto subscribed my name in the presence of two witnesses.

DANIEL B. LUTEN.
